BALL WINDING MACHINE

Raymond S. Francis, Rumford, R. I., assignor to
 United States Rubber Company, New York,
 N. Y., a corporation of New Jersey

Application October 30, 1940, Serial No. 363,452

15 Claims. (Cl. 242—3)

This invention relates to machines for winding spherical bodies with strands of flexible or elastic material, to produce golf-balls for example, and the invention relates more particularly to improvements in the ball winding machine of the H. Z. Cobb Patent No. 1,270,009.

The machine of this Cobb patent is an excellent golf ball winding machine and it has been extensively used for many years.

During the last few years a demand has developed for a very hard golf ball produced by winding the rubber strand under the highest tension it is practical to use. When a golf ball is produced on the machine of the Cobb patent by winding the ball under this high tension, chafing of the rubber thread occurs, resulting in thread breakage. The amount of thread breakage which has occurred in winding any ball may be readily determined by unwinding the rubber thread from the ball to determine how many breaks appear, and whether or not serious chafing has been caused by the winding apparatus.

The present invention contemplates various improvements in the winding machine of the Cobb patent whereby a golf ball may be wound under the extremely high thread tension now desired, without chafing the ball or breaking the rubber thread.

The ball winding machine of the present invention, like that of the Cobb patent, is provided with two similar rotating heads adapted to support and rotate the ball upon the longitudinal axis upon which the heads rotate. These heads are supported to move yieldingly away from each other as the size of the ball increases, and each head is provided with a pair of discs which cooperate with the discs upon the other head to support and rotate the ball.

One important feature of the present invention resides in the construction whereby no metal parts engage the ball during the thread winding operation. Another important feature resides in the construction whereby chafing of the ball is avoided as the supporting discs are operated to turn the ball in the rotating heads from one axis to another.

A further important feature resides in the use of rubber tires upon the discs to decrease the danger of chafing the ball, and in means for clamping each tire to its disc to prevent the tire from creeping thereupon as the disc is positively driven to shift the ball from one axis of rotation to another.

These ball supporting discs are necessarily mounted close together upon the heads so as to 55

support the small ball center at the beginning of the ball winding operation, and there is therefore not much space between these discs. A further feature of the present invention therefore resides in means which may be readily operated from the outer surface of a head to release a disc so that it may be removed when it is desired to change the rubber tire upon the disc.

A further feature of the present invention resides in an idler cylinder mounted on each head in position to retain the ball in engagement with the discs and which is supported for both rotating and sliding movement, so that it may slide freely as the ball is shifted to a different axis. 15 This free sliding movement of the cylinder avoids chafing the ball as it is turned within the heads. The cylinder is formed of rubber or is rubber faced to avoid chafing the ball.

Still another feature of the present invention resides in mechanism for periodically and independently rotating the two discs of each head by mutilated gears constructed to cause one disc upon a head to dwell once during its complete revolution, and the other disc upon this head to 25 dwell twice during its complete revolution, so as to turn the ball frequently in the heads on different axes. A further feature resides in flat spots on the discs adapted to form cooperating pole supports for the ball as it is turned to a 30 new axis.

The above and other features of the invention and novel combination of parts will be more fully understood when read in connection with the accompanying drawings illustrating one good practical embodiment of the invention.

In the drawings:

Fig. 1 is a front elevation with parts in section of a bench type of golf ball winding machine embodying the features of the present invention;

40 Fig. 2 is a top plan view with parts in section of the construction of Fig. 1;

Fig. 3 on a larger scale is a longitudinal sectional view through one of the heads and the operating mechanism for the same;

45 Fig. 4 is a transverse sectional view through the head of Fig. 3;

Fig. 5 is a face view of a pair of cooperating mutilated gears having one dwell;

Fig. 6 is a similar view of a pair of cooperating mutilated gears having two dwells;

Fig. 7 is a sectional view through one ball supporting disc and the means for supporting and rotating the same;

Fig. 8 is a view showing how a ball is supported

by the four discs and cooperating idler cylinders; and

Fig. 9 is a diagrammatic view illustrating how the ball is turned upon different axes by the supporting discs.

The drawings illustrate what is known as a bench type of golf ball winding machine and the various operating parts are housed within the hollow metal frame 10 having the housing 11 at its left hand end and the housing 11' at its right hand end. Between these housings is provided a clearance space in which the golf ball supporting heads 12 and 12' rotate. These two heads are similar in construction and operation as is also the mechanism for supporting and operating each head. Therefore the description of one will suffice for the other.

In the lower portion of the hollow frame 10 is mounted a main drive shaft 13 which extends longitudinally of this frame and serves to operate both heads. This shaft is driven by the grooved pulley 14 secured thereto and adapted to be rotated by V-belts from a motor (not shown) but which is usually located beneath the frame 10. The shaft 13 is journaled near each end thereof in the bearings 15 and 15' which are shown as supported in a suspended condition from the top and side walls of the housings 11, 11' by the flanges 16, 16'.

The shaft 13 is provided at its opposite ends with the gears 17, 17', and adjacent these gears are provided the slightly larger gears 18 and 18'. The gears 18 and 18' serve to rotate the heads 12 and 12' respectively and the slightly smaller gears 17, 17' serve to rotate the ball supporting discs within the heads as will be more fully hereafter explained.

Within the housing 11 is mounted for longitudinal sliding movement the shaft supporting sleeve 19, and within the opposite housing 11' is mounted a similar sleeve 19'. The sleeve 19 is supported for limited sliding movement within the bearings 20 and 21, and it is provided with an integral flange 22 having a notched portion in its upper edge adapted to slidably engage a fixed pin 23 secured in a wall of the housing 11. The construction is such that the sliding engagement between the flange 22 and pin 23 holds the sleeve 19 against rotation.

The sleeve 19 is provided with an annular groove or recess 24 adapted to be engaged by anti-friction rollers provided at the upper ends of the spaced arms 25 and 26 which arms together form a yoke that engages the opposite sides of the sleeve 19 and serves to impart sliding movement to the sleeve. The arms 25 and 26 are rigidly secured to and extend upwardly from the transversely extending shaft 27, to which shaft is also rigidly secured the longitudinally extending arm 28.

The bell crank lever formed of the transversely extending shaft 27, upwardly extending arms 25 and 26 and longitudinally extending arm 28 constitutes means for imparting sliding movement to the sleeve 19 and head 12, to move the head towards and from the ball supporting position. A similar bell crank lever consisting of the upwardly extending arms, transversely extending shaft 27' and longitudinally extending arm 28' serves to impart a sliding movement to the sleeve 19' and its head 12', and in order that the same sliding movement may be imparted to both heads the arms 28 and 28' extend towards each other at the back of the machine into overlapping relation as will be apparent from Fig. 2,

where they are connected by a sliding block 29 which serves to impart the movement of one arm to the other.

The portions of the arms 28 and 28' which are connected by the sliding block 29 are continuously urged downwardly by the weight supporting means 30 which is secured to an ear 31 formed upon one of these arms. This weight supporting means is provided with as many weights 32 as desired to thereby urge the heads 12 and 12' against the ball B, to be wound, with the required amount of force. When it is desired to separate the heads 12 and 12' to move them out of engagement with the ball this may be done by manually pushing rearwardly the upwardly extending lever 33 disposed at the rear of the machine adjacent the housing 11' and rigidly secured to its supporting shaft 34 that is rockingly mounted in the brackets 35 and 36 secured to the rear portion of the frame 10. Rigidly secured to this shaft 34 and extending forwardly therefrom into the frame 10 is the arm 37, the inner end of which projects under the arm 28' to lift the latter when the hand lever 33 is pushed rearwardly, this serves to raise both arms 28, 28' and force the heads 12, 12' apart.

The purpose of the sleeve 19 is to rotatably support the head 12 and to slide it towards and from the ball winding position. The construction of this sleeve and the mechanism for supporting and rotating the head 12 is best shown in Fig. 3 wherein it will be seen that the sleeve 19 is provided near its ends with the anti-friction bearings 38 adapted to rotatably support the head operating hollow shaft 39. To the inner end of this hollow shaft is rigidly secured an annular flange 40 to which is bolted the head 12, and to the opposite end of the shaft 39 is rigidly secured by the set screw 41, the operating gear 42. This gear 42 meshes with the above-mentioned gear 18 upon the main drive shaft 13. The arrangement is such that rotation of the shaft 13 serves to drive the head 12 through the shaft 39 and cooperating gears 18 and 42, and at the same time the head 12' is similarly driven by its hollow shaft and cooperating gears 42' and 18'.

The mechanism described serves to impart the same rotating movement to the heads 12 and 12' and to hold them rigidly in engagement with the ball B to thereby wind the rubber thread or tape T about the ball in a plane at right angles to the longitudinal axis of the shafts 39 and 39'. It is necessary, however, in order to wind a ball or sphere by the present mechanism to shift frequently the axis upon which the ball B is being rotated in order to distribute the windings of the thread evenly around the ball. The means for shifting this ball to different axes of rotation with respect to the heads 12 and 12' will now be described.

Within the head 12 are rotatably mounted the ball supporting discs a and b and within the head 12' are rotatably mounted the similar ball supporting discs c and d. These four discs are preferably tapered as shown, and the discs upon one head cooperate with the discs upon the other head to support and rotate the ball. The turning of the ball B from one axis to another is secured by positively but intermittently rotating these four discs with respect to their supporting heads at a very slow speed compared with the speed at which the heads 12 and 12' are rotated.

The means for imparting the desired rotating movement to the discs *a* and *b* mounted within the head *12* comprises the longitudinally extending shaft *43* journaled within the bearings *44* to rotate within the hollow shaft *39*. This shaft *43* is provided at its outer end with the gear *45* which meshes with the gear *17*. The gears *42* and *45* are preferably made of fiber or other non-metallic material and the gear *45* is slightly larger than the gear *42*, and may have one more tooth than the gear *42*. The purpose of this is to rotate the shaft *43* slowly within the shaft *39* during the ball winding operation. This serves to rotate the bevel gear *46* slowly in the head *12*. The gears *17* and *18* are wide enough to engage the gears *45* and *42* respectively throughout their sliding movement.

Within the head *12* is rotatably mounted the transversely extending shaft *47* which has rigidly secured thereto a bevel gear that meshes with the bevel gear *46*. This construction serves to rotate the transversely extending shaft *47*. To one end of the shaft *47* is rigidly secured the mutilated gear *48* and to the other end of this shaft is rigidly secured the mutilated gear *49*. As will be apparent from Figs. 5 and 6, the mutilated gear *48* is provided with one smooth convex surface whereas the mutilated gear *49* is provided with two of these surfaces disposed at nearly diametrically opposite sides of the gear.

Within the head *12* is also rotatably mounted the stub shaft *50* to the inner end of which is removably secured the disc *b*, and the stub shaft *51* to the inner end of which is removably secured the disc *a*. To the outer end of the stub shaft *50* is rigidly secured the mutilated gear *52* which is operated by the gear *48* as best shown by Fig. 5, and to the outer end of the stub shaft *51* is rigidly secured the mutilated gear *53* which is operated by the mutilated gear *49* as best shown in Fig. 6. The construction of these mutilated gears is such that the smooth convex portion of the driver gear cooperates with the concave portion of the driven gear to impart a dwell to the latter.

The discs *c* and *d* within the head *12'* are positively operated by mechanism similar to that just described and the arrangement is preferably such that during the ball winding operation an intermittent rotating movement is imparted to all four discs to operate them as follows during one complete rotation of the shaft *47*: (1) all four discs are rotated together through a small angle to thereby rotate the ball *B* on the axis *XX* of Fig. 9, (2) then the diagonally opposite discs *a* and *d* are rotated while the discs *b* and *c* are held against rotation within their respective heads to thereby rotate the ball on the axis *YY*, (3) then the discs *b* and *c* are rotated while the discs *a* and *d* are held against rotation to thereby turn the ball upon the axis *ZZ*, and (4) then the discs *a* and *d* are again rotated while the other two discs are held against rotation to turn the ball upon the axis *YY*, thus completing one complete cycle of operation. This series of operation serves frequently to shift the axis of the ball *B* as the same is being rapidly rotated upon the axis *WW* by the rotating heads *12*, *12'* to wind the tape *T* about the ball *B*. To secure these series of operation it is necessary that the gears *48* and *49* be fastened to the opposite ends of the shaft *47* so that the dwell of the gear *48* is disposed at the proper angle to the dwells of the gear *49*.

As above stated, there is now a demand for golf balls which are wound under very high tension and the primary purpose of the present

invention is to facilitate the winding of a ball under this high tension without chafing the ball or breaking the thread. To this end an important feature of the present invention resides in the construction whereby no metal parts engage the ball during the winding operation. Therefore, in accordance with the present invention each of the discs *a*, *b*, *c* and *d* which may be formed of metal is provided with a rubber tire *R* as best shown in Fig. 7. Since these discs are positively driven periodically within their heads to turn the ball from one axis to another, it is important that provision be made for preventing the tires *R* from slipping upon these discs. Therefore a further feature of the present invention resides in means which will now be described for firmly clamping each tire to its disc to prevent it from creeping, and another feature resides in the construction whereby these discs may be easily removed from the heads to facilitate the changing of the tires when this becomes necessary.

These objects are secured by the construction best shown in Fig. 7 wherein it will be seen that the stub shaft *50* is made hollow, to receive the clamping bolt *54* which extends axially through this stub shaft and is formed with a hexagonal head at its outer end adapted to receive an operating wrench. The shaft *50* is provided at its inner end with the integral plate *55* against which one face of the disc *b* may rest when the disc is secured to this shaft. The opposite face of this disc *b* is constructed to be engaged by the clamping head or plate *56* which is threaded at *57* to receive the threaded inner end of the clamping bolt *54*. The arrangement is such that the bolt *54* serves to clamp the disc *b* firmly to the inner end of the stub shaft *50*, and the plates *55* and *56*, serve to clampingly engage the peripheral side portions *58* and *59* of the tire *R* to thereby firmly secure the tire to its disc to prevent its creepage thereupon.

It is important in order that the above described dwells may come right, that when a disc is removed from its stub shaft, it be turned to its proper angular position with respect to that shaft when it is again secured thereto. Therefore in order to secure the disc *b* to its shaft *50* in the proper angular relation therewith, the construction shown in Fig. 7 is employed wherein the head *56* is provided with the pin *60* which is adapted to pass through a hole *61* in the disc *b* and into the hole *62* in the plate *55* to secure these parts together in proper alignment, and to positively drive the disc *b* from its shaft *50*. It is to be understood that each of the discs *a*, *b*, *c* and *d* is secured to its operating shaft by mechanism such as shown in Fig. 7 so that any one of these discs may be easily and quickly removed by operating the bolt *54*. To this end the cover plates *63* at each side of the heads *12* and *12'* are provided with a wrench receiving hole closed by the nut *64* which may be removed when a wrench is to be engaged with the head of the bolt *54* to operate the same. It will be seen from the foregoing that the bolt *54* serves not only to removably secure a disc to its shaft *50* or *51* but also to clamp the tire *R* to its disc so that creepage of the tire is prevented.

When the ball *B* is being turned on either the axis *YY* or *ZZ* of Fig. 9 it is important to reduce the pressure at this instant upon the ball at the poles upon which it is being rotated, to thereby lessen the friction upon the ball at this time. Therefore, in accordance with the present inven-

tion the discs *b* and *c* which receive one dwell each during a complete rotation are each provided with one flat spot *S* (see Fig. 9) upon their periphery, and the other two discs *a* and *d* which receive two dwells during one complete revolution are each provided with two flat spots (not shown) so positioned that they will engage the ball at the time it is being supported by these discs for rotation by the other pair of discs.

In order to hold the ball, irrespective of its size, in proper engagement with the cooperating discs *a*, *b*, *c* and *d*, there is provided in each head *12* and *12'* in accordance with the present invention an idler cylinder *65* which is mounted to rotate in engagement with the ball and also for free sliding movement in the direction of its length. To this end the cylinder *65* is rotatably and slidably supported in the head *12* by a fixed shaft *66* which is considerably longer than the cylinder as shown in Fig. 8 so that the cylinder may slide an inch or so lengthwise of this shaft. A relatively light coiled spring *67* is preferably provided about the shaft *66* near each end thereof and is confined between an end of the cylinder and the shaft supporting wall of the head *12* to thereby yieldingly hold the cylinder *65* spaced from the supporting walls of the head *12* as shown in Fig. 8. The cylinder *65* is conveniently formed of fiber so that it will rotate and slide freely on the shaft *66* and is preferably provided with a rubber jacket on its outer surface to avoid chafing the ball *B*.

When the ball is being turned upon the axis *YY* or *ZZ* as above described, the cylinders *65* will at this instant be shifted by the ball to the dotted line positions in which they are shown in Fig. 8. This relieves the ball from the chafing that would occur at this time if these cylinders were not free to slide in the direction of their length.

The rubber thread or tape *T* to be wound upon the ball *B* under tension is supplied to the winding point under the desired tension from a source of supply not shown. The movement of the heads towards each other may be arrested at the desired point by adjusting the stop bolts *68*, *68'* in the housings *11*, *11'* to engage the flanges *22*, *22'*. When the ball *B* has reached a predetermined size the winding operation may be stopped by causing an electric switch to be actuated to stop the operating motor. To this end a switch box *69* is tiltingly mounted on the arm *28* in position to engage the adjustable stop bolt *70*. The arrangement is such that the heads will be forced apart by the increasing size of the ball until the upward movement of the arm *28* engages the switch box *69* with the stop bolt *70* to thereby stop the operating motor.

Having thus described my invention, what I claim and desire to protect by Letters Patent is:

1. In a ball winding machine, opposed rotatable ball holding heads, a pair of tapered discs on each head, the discs on one head being adapted to cooperate with the discs upon the other head to support and rotate the ball on the axis about which the heads rotate, power means for rotating said heads and for turning the discs relative to the heads, a free rotating and sliding idler cylinder on each head positioned to retain the ball in engagement with the discs and adapted to slide freely as the ball is turned to a different axis to thereby avoid chafing the ball.

2. In a ball winding machine, opposed rotatable ball holding heads, a pair of tapered discs on each head, the discs on one head being adapted to cooperate with the discs upon the other head

to support and rotate the ball, power means for rotating said heads to rotate the ball upon the axis about which the heads rotate, power driven stub shafts in the heads to turn the discs relative to the heads, means operable from the outside of the heads for removably securing each disc to the inner end of its stub shaft so that one disc can be removed without disturbing the other discs, and a yielding cover for each disc.

3. In a ball winding machine, opposed rotatable ball holding heads, a pair of discs on each head, the discs on one head being adapted to cooperate with the discs upon the other head to support and rotate the ball, power means for rotating said heads to rotate the ball upon the axis about which the heads rotate, power driven stub shafts in the heads to turn the discs relative to the heads, clamping means operable from the outside of the heads for removably securing each disc to the inner end of its stub shaft so that one disc can be removed without disturbing the other discs, and a yielding cover for each disc clamped thereto by said clamping means.

4. A rotating head for a ball winding machine, a pair of spaced, cooperating ball-engaging discs on said head, means for rotating the discs in said head including a power driven stub shaft for each disc, clamping means operable from the outside of the head for removably securing a disc to its shaft, and a tire for each disc and secured to the disc by said clamping means.

5. A rotating head for a ball winding machine, a pair of spaced, cooperating ball-engaging discs on said head, means for rotating the discs in said head including a power driven stub shaft for each disc, clamping means operable from the outside of the head for removably securing a disc to its shaft, a tire adapted to fit over said disc with a periphery disposed at the inner and outer face of the disc, and means operable by said clamping means for gripping both peripheries of the tire to hold it from creeping on the disc.

6. A rotating head for a ball winding machine, a pair of spaced, cooperating ball-engaging discs on said head, means for rotating the discs in said head including a power driven stub shaft for each disc, a tire for each disc, means for removably securing a disc to its shaft including an inner plate, an outer plate and clamping means operable to clamp said disc and its tire between said plates.

7. A rotating head for a ball winding machine, a pair of spaced, cooperating ball-engaging discs on said head, means for rotating the discs in said head including a power driven stub shaft for supporting and driving each disc, a tire for each disc, and clamping means extending axially through each stub shaft and operable to clamp a tire to its disc to prevent the tire from creeping.

8. A rotating head for a ball winding machine, a pair of spaced, cooperating ball-engaging discs on said head, means for rotating the discs in said head including a power driven stub shaft for each disc, a tire for each disc, and clamping means associated with each disc for clamping the tire to its disc to prevent the tire from creeping.

9. A rotating head for a ball winding machine, a pair of spaced, cooperating ball-engaging discs on said head, means for rotating the discs in said head including a power driven stub shaft for each disc, a tire for each disc, and clamping means associated with each stub shaft and operable from the outer face of said head for clamp-

ing the tire to its disc to prevent the tire from creeping.

10. In a ball winding machine, opposed rotatable ball holding heads, a pair of discs on each head, the discs on one head being adapted to cooperate with the discs upon the other head to support and rotate the ball, means for rotating the heads, means for rotating the discs in their heads including a hollow stub shaft for supporting and turning each disc, a tire for each disc, and clamping means extending through the hollow portion of each stub shaft and operable to clamp the tire to its disc to prevent the tire from creeping.

11. In a ball winding machine, opposed rotatable ball holding heads, a pair of discs on each head, the discs on one head being adapted to cooperate with the discs upon the other head to support and rotate the ball, means for rotating the heads, means for rotating the discs in their heads including a hollow stub shaft for supporting and turning each disc, a tire for each disc, a bolt extending axially through each hollow stub shaft and operable from the outer face of the head to clamp a tire to its disc.

12. In a ball winding machine, opposed rotatable ball holding heads, a pair of discs on each head, the discs on one head being adapted to cooperate with the discs upon the other head to support and rotate the ball, means for rotating the heads, means for periodically and independently rotating the two discs of each head, including a stub shaft for one disc having a mutilated driving gear with one dwell and a stub shaft for the other disc having a mutilated driving gear with two dwells, to thereby turn the ball frequently on different axes as it is rotated by said heads.

13. In a ball winding machine, opposed rotat-

able ball holding heads, a pair of discs on each head, the discs on one head being adapted to cooperate with the discs upon the other head to support and rotate the ball, means for rotating the heads, means for periodically and independently rotating the two discs of each head, including a stub shaft for one disc having a mutilated driving gear with one dwell and a stub shaft for the other disc having a mutilated driving gear with two dwells, and each disc having a flat spot for each dwell adapted to form a pole support for the ball as the ball turns on a new axis.

14. In a ball winding machine, opposed rotatable ball holding heads, a pair of discs on each head, the discs on one head being adapted to cooperate with the discs upon the other head to support and rotate the ball, means for rotating the heads, and for turning the discs relative to the heads, a rubber faced idler cylinder supported on each head for rotating and sliding movement to retain the ball in engagement with the discs and adapted to slide freely as the ball is turned to a different axis, and a yielding tire on each disc, whereby no metal engages the ball as it is wound.

15. In a ball winding machine, opposed rotatable ball holding heads, a pair of discs on each head, the discs on one head being adapted to cooperate with the discs upon the other head to support and rotate the ball, means for rotating the heads, means for periodically and independently rotating the two discs of each head so as to cooperate with the discs of the other head to turn the ball from one axis to another, a tire for each disc, and flat spots on the discs adapted to form pole supports for the ball as it turns to a new axis.

RAYMOND S. FRANCIS.
